UNITED STATES PATENT OFFICE.

CLAUDE IVES MC LAINE, OF BOSTON, MASSACHUSETTS, ASSIGNOR TO SEAL-KAP COMPANY, OF NATICK, MASSACHUSETTS, A CORPORATION OF MASSACHUSETTS.

CLOSURE FOR CONTAINERS.

Application filed January 22, 1923. Serial No. 614,158.

This improvement in the closure art has to do primarily with the combined effect of positiveness in seal and prevention in unauthorized removal.

5 In the general class of seals or closures to which my invention applies it has been old and accepted practice to form upon the mouth of the container a closure or sealing member so conforming to the structure of 10 the mouth as to interlock therewith.

In such easily deformable closures as those of non-metallic material, sufficient deformation for removal is possible without such distortion as to render detection of replacement easy.

15 While my invention is capable of a wide range of usefulness I have selected as illustrative of my invention a popular type of closure for milk bottles such as is quite generally used in the urban delivery of milk and cream. While I have selected a rather specific form of closure as illustrative of my invention it will be understood that such is 20 illustrative rather than limiting and that various modifications in type and structure may be employed without departing from the spirit of my invention.

25 In general my invention contemplates the combination with closures of such types 30 with a positive locking member expansible or otherwise extensible to compel positive interengagement of the closure and the container mouth or neck.

To proceed without delay to the specific 35 form selected for illustration and discussion, I invite attention to the combination of the closure and the container of well known type with a member capable of insuring positive interengagement while at the same 40 time forming a sealing, interference with which will be at once discernible and evident.

Throughout the specification and drawings like reference characters are employed to indicate corresponding parts, and in the 45 drawings:

Fig. 1 is a central vertical section through a container mouth with closure and seal applied.

Fig. 2 is a plan view thereof, and 50 Fig. 3 a view of a characteristic locking member or seal.

The container type selected as above stated is the so-called milk bottle type and the closure type selected is the pulp or paper 55 closure generally accepted as the most eco-

nomic and best suited to conditions of lac- 60 tic distribution.

In the drawings I have indicated at 1 the neck of such a container having a mouth 2 and an external bead or lip 3. Internally 65 the delivery orifice is grooved to form a shoulder 4 which under most State laws means a definite filling level indicating the necessary surface level of the content to conform to standard measure. This internal 70 annular groove indicated at 9 is defined on its lower edges by the shoulder or shelf 4 and on its upper edge by the inward or over- hanging bead 10 of the bottle mouth.

This is one of the commercial requisites 75 of standard sealing by which the definite standard commercial form of containers may be made to meet the shifting and exacting requirements of legislation and rule.

The illustrated container and mouth por- 80 tion are quite stereotyped and general and cannot be commercially varied without great economic waste in stock and in manufacturing equipment.

My illustration has therefore point in its 85 practical application. The closure for such a container is generally a simple disc forced to seat on the shoulder 4 for a more general sanitary and efficient seal such as shown. Such a seal comprises a disc 5 having a mar- 90 ginal flange consisting of an arched annulus 6 crimped as at 7 to take the stock from the flat blank from which such caps are usually formed. The crimping is formed or form- 95 able in the process of manufacture or the seating of the cap on the container.

In accordance with my invention in seat- 100 ing or crimping the cap on the container I can produce into the combination an expansible or otherwise positive engageable mem- 105 ber 8. As shown this member is a crimped or corrugated circular piece or ring. I have found that a flat metallic corrugated or undulated ribbon is very satisfactory, but ob- 110 viously this member may be of wire, resilient or otherwise, and variously expandible for the purpose. The ring may be soldered as at 8' or integral.

When the bottle or container is capped or closed, the expansion tool usually used in setting the form of cap selected for illustration may be employed to seat or drive home the expansion member 8. When seated as shown in Fig. 1, the member 8 is posi- 115 tively set so that any removal of the cap ne-

cessitates the removal or deformation or rupture of the locking member 8. My invention therefore provides a means of positive interlock as well as a seal or guard against unauthorized tampering.

As indicated above, my invention is capable of various embodiments and modifications to meet various conditions or changes in law or rulings and all without departing from the spirit of my invention if within the limits of the appended claims.

What I therefore claim and desire to secure by Letters Patent is:

1. In combination with a container having

an internal annular recess about its mouth, 15 of a conformable closure engageable therewith, and a corrugated locking member disposed against said closure adjacent said recess.

2. A closure for a container having an internal annular recess about its mouth comprising a conformable delivery sealing and recess engaging member, and a corrugated sealing member expansively associated therewith.

In testimony whereof I affix my signature.

CLAUDE IVES McLAIN.
